KNOCK-DOWN PROJECTION ROOM

Guy W. Garrard and Elmer J. Peery, Bakersfield,
Calif.

Application May 20, 1937, Serial No. 143,798

1 Claim. (Cl. 88—24)

This invention relates to knock-down projection rooms and has for an object to provide a portable miniature projection room especially adapted for library, sales rooms, school rooms, 5 or similar locations where it may be used regularly for showing pictures without darkening the rooms.

A further object is to provide a device of this character which will be formed of a few strong 10 simple and durable parts, which will be inexpensive to manufacture and which will not easily get out of order.

With the above and other objects in view the invention consists of certain novel details of 15 construction and combinations of parts herein-after fully described and claimed, it being understood that various modifications may be resorted to within the scope of the appended claim without departing from the spirit or sacrificing any 20 of the advantages of the invention.

In the accompanying drawing forming part of this specification,

Figure 1 is a front elevation of a projection room constructed in accordance with the invention.

Figure 2 is a longitudinal sectional view of the projection room taken on the line 2—2 of Figure 1.

Figure 3 is an enlarged cross sectional view of the projection room taken on the line 3—3 of Figure 2.

Figure 4 is a perspective view of one of the corner pieces.

Figure 5 is a cross sectional view of the parts 35 disassembled and arranged in a neat package for transportation or storage.

Referring now to the drawing in which like characters of reference designate similar parts in the various views, 10 designates a corner piece, 40 the same being right-angular in cross section and being formed of rigid material, molded, cast, pressed or otherwise constructed. The legs of the corner piece are provided with longitudinal grooves 11 in the edges to receive the longitudinal edges of the side and top and bottom panels 12 which may be formed of any light, 45 strong, durable opaque material. There are preferably four longitudinal corner pieces and four panels and the panels are tapered from the 50 leading end toward the rear end so that when the panels are assembled with the corner pieces the projection room will be substantially of truncated rectangular prism contour, as best shown in Figure 1.

Bolts 13 are passed through the panels and 55 through the corner pieces near the ends thereof to detachably secure these parts together so that the device may be readily disassembled and arranged in a neat compact package for transportation or storage.

The front and rear ends of the panels and corner pieces are supported by substantially rectangular frame like channel finishing pieces 14, best shown in Figure 2, which may be likewise formed of rigid material, molded, cast, pressed or otherwise constructed. The two frame like finishing pieces are of different respective sizes so that one may embrace the large rectangular front end of the structure projection room and the other may embrace the smaller diameter rear 10 end of the structure. Also the smaller may be telescopically received into the larger frame like finishing piece, as shown in Figure 5, when the device is knocked down for transportation or storage. The same bolts 13 which secure the 15 panels to the longitudinal corner pieces secure the frame like finishing pieces in place.

A screen 15 of sufficient size to snugly fit in the rear end of the projection room is provided, the screen being formed of any desired material, 20 such as for instance heavy composition board having a front reflecting surface formed by painting, for example with aluminum paint, or otherwise. The screen is adhesively secured to a back plate 16 formed integral with the rear frame 25 like finishing piece 14, as best shown in Figures 2 and 5 or may be otherwise secured in place.

In use, the projection room may be set upon a suitable table or other support with the front open end toward the projecting machine. When 30 the image is projected upon the screen the opaque panels provide a dark surface which will eliminate darkening of the room when the device is constructed as above described.

From the above description it is thought that 35 the construction and operation of the invention will be fully understood without further explanation.

What is claimed is:

A knock-down projection room comprising a 40 plurality of corner pieces of right angular cross section having longitudinal grooves in the edges of the legs, side, top and bottom panels having longitudinal edges engaged in said grooves, said panels tapering from a wide front end to a narrower rear end, substantially rectangular front and rear frame like finishing pieces having channels receiving respectively the front and rear edges of the panels and the ends of the longitudinal corner pieces, bolts passed through the ends 45 of the corner pieces and panels and through the front and rear frame like finishing pieces to collapsively secure the parts together, a back plate 50 connected to the rear frame like finishing piece and forming a closure for the rear end of the 55 projection room, and a screen secured to the front face of said back plate.
